UNITED STATES PATENT OFFICE

108,286

DESIGN FOR A SOLE OR SIMILAR ARTICLE

Don C. Hubbard, Auburn, Maine

Application April 25, 1936, Serial No. 62,309

Term of patent 14 years

To all whom it may concern:

Be it known that I, Don C. Hubbard, a citizen of the United States, residing at Auburn, county of Androscoggin, State of Maine, have invented a new, original, and ornamental Design for a Sole or Similar Article, of which the following is a specification, reference being had to the accompanying drawing, forming part thereof.

Fig. 1 is a plan view of a sole or similar article, showing my new design, and

Fig. 2 is a diagrammatic longitudinal sectional view, on a slightly reduced scale.

I claim:

The ornamental design for a sole or similar article, as shown.

DON C. HUBBARD.
